UNITED STATES PATENT OFFICE

THOMAS GLEN, JR., OF COOGEE, SYDNEY, NEW SOUTH WALES, AUSTRALIA

FLOOR POLISHER

Application filed January 12, 1929. Serial No. 332,169.

The invention relates to what are generally known as floor polishers, and, more particularly to the kind thereof having a receptacle for oil or other liquid polish small quantities of which may, from time to time, be deposited directly upon the floor.

The invention is illustrated in the drawing wherein:—

- Fig. 1 is a side elevation.
- 10 Fig. 2 a corresponding plan.
- Fig. 3 a sectional elevation to a larger scale.
- Fig. 4 a part sectional view.

The body 1 which may be of wood has a receptacle 2 for liquid polish which is passed 15 into it through an opening closed by a plug 3.

The rear of the body has a gap 4 and a pipe 5 projecting from the bottom of the receptacle into the gap, has at its outer end a port 20 closable by a pin valve 6, projecting from a crank lever 7 which is pivoted at 8 upon a bracket 9 fixed to the body at the end of the gap.

A coil spring 10 connected to lever 7 and to bracket 9 tends to keep the port in pipe 5 25 closed by the pin valve 6.

One arm of crank lever 7 is connected by a chain 11 or flexible material to the end of a slide rod 12 which lies in a recess 13 in a handle 14 the end whereof has a socket 15 30 having the spring arms 16 fixed upon it the ends of which engage in holes in the sides of the gap 4 and form a pivotal connection for handle 14 with the body.

The upper end of the slide rod is connected 35 by a cross pin 17 with a ferrule 18 slidable upon handle 14 which has a longitudinal slot 19 guiding the pin.

The lower face of the body has attached to it a spreading surface 20 of sheepskin with 40 the wool upon it, or other similar material, which is held in position by a clip of spring wire 21 encased in a hem 22 of the material and received in a groove 23 in the body.

The opposite face of the body has the pol- 45 ishing surface of ordinary polishing mate-

rial held in position by a clip of spring wire 24 encased in a hem 25 of the material and received by a groove 26 in the body.

This method of connecting the material to the body facilitates its removal therefrom.

When the apparatus is in the position indicated in Fig. 3, the pin valve is readily operable by sliding the ferrule 18 upon the handle and a desired quantity of oil is thereby permitted to pass from the receptacle to the floor which is to be polished.

When however the apparatus is turned over with the polishing surface in contact with the floor the handle turns upon its pivotal connection downwardly and the flexible medium 11 being slackened movement of the ferrule has no effect upon the pin valve which remains closed.

I claim:—

1. In a floor polisher the combination of a body, a receptacle therein, a pipe from the receptacle located in a gap in the body, a crank lever pivoted within the gap, a pin valve upon the crank lever adapted to close the end of the pipe, a spring operating upon the crank lever, a handle having a longitudinal recess, a slide rod therein, and a flexible medium connecting the crank lever to the slide rod substantially as specified and illustrated.

2. In a floor polisher the combination of a body, a receptacle located therein, the body having a rearwardly located gap, a pipe from the receptacle projecting into the gap, a bracket fixed in the gap, a crank lever pivoted thereon, a pin valve upon the crank lever adapted to close the end of the pipe, a spring connecting the crank lever to the bracket, and means for operating the crank lever substantially as described herein and illustrated.

In testimony whereof I have signed my name to this specification.

THOMAS GLEN, JUNIOR.
